UNITED STATES PATENT OFFICE.

GUSTAVE ADOLPH WENDT, OF SPOKANE, WASHINGTON.

REVOLVING-CYLINDER GAS-ENGINE.

1,111,048.

Specification of Letters Patent. Patented Sept. 22, 1914.

Application filed March 31, 1913. Serial No. 757,818.

To all whom it may concern:

Be it known that I, GUSTAVE ADOLPH WENDT, a citizen of the United States, residing at Spokane, in the county of Spokane and State of Washington, have invented new and useful Improvements in Revolving-Cylinder Gas-Engines, of which the following is a specification.

My invention relates to an improved form 10 of revolving cylinder gas engine, and has as its principal object to eliminate difficulties of ignition in multiple cylinder engines.

A second object is to improve and simplify the valve mechanism of multiple cylinder engines.

A final object resides in the particular arrangement and combination of parts hereinafter described.

In the accompanying drawings:—Figure 20 1 is a side view in elevation. Fig. 2 is a view similar to Fig. 1 having a portion broken away to show valve actuating mechanism. Fig. 3 is a side elevation of the machine shown in Fig. 1 taken from the opposite direction. Fig. 4 is a view of the same machine in end elevation. Fig. 5 is a section taken on the line 5—5 of Fig. 7. Fig. 6 is an enlarged detail sectional view of one of the cylinders and pistons shown in Fig. 5. Fig. 7 is a section taken on line 7—7 of Fig. 3 looking in the direction of the arrows. Fig. 8 is an enlarged sectional view taken on the line 8—8 of Fig. 5. Fig. 9 is a detail of one of the valves used to govern 35 the explosive mixture. Figs. 10 and 11 are details of the valves used in the compression of the explosive mixture.

In the separate views the same part is designated by the same reference character.

40 Referring more particularly to the drawings, 1 is a cylindrical casing as best shown in Fig. 7, one face of the casing being provided centrally thereof with a chamber 12 which is closed on its outer side by a sprocket 45 wheel 34. The wheel 34 is rigidly mounted on the fixed shaft 23. It will be understood that there is a running fit between the edge of the chamber 12 and said sprocket wheel. The sprocket wheel 34 appears also in Fig. 50 3 and as clearly appears in said figure, a pipe 10 leads into the chamber 12 through the sprocket 34. The pipe 10 is connected to a carburetor of any suitable type and serves for introducing an explosive mixture 55 into the chamber 12. Radiating from the chamber 12 are pipes 2, there being one such

pipe for each of the explosion cylinders. An explosion cylinder 3 radiates from the inner cylindrical casing 1 as clearly shown in Figs. 1, 2 and 3, and the pipes 2 enter the cylinders 3 at their inner ends, or in other words, close to the casing 1. Within each cylinder 3 is a piston 4. The inner ends of the cylinders 3 are closed by heads such as 5 and as the pistons 4 are shorter than usual in order to economize weight, the heads 5 are apertured to receive the rods 38 which project inwardly from the pistons 4 in order that the pistons may always be held in alinement. The central portions of the heads 5 are provided with inwardly extending ridges such as 6, best shown in Figs. 7 and 11, and the piston rods 7 which are pivoted to the pistons as at 8, pass through the heads 5 intermediate the ridges 6. In order to close 75 the interior of the casing 1 against the interior of the cylinders 3, I provide sliding members 15 through which the piston rods 7 pass but which make a sliding fit with the ridges 6. The pipes 2 are provided with apertured portions which connect with the cylinders 3 and, as shown in detail in Fig. 10, the axially extending portions of the pipes 2 contain inlet valves 13 which are normally held closed by means of a spring 80 15'. It will be seen also from an inspection of Fig. 11 that the cylinder heads 5 are provided with spring operated outlet valves 16 which afford a passage therethrough and serve to connect the interior of the cylinders 3 below the pistons 4 with the interior of 85 the casing 1. Now if we consider a piston 4 such as the one shown in the upper part of Fig. 7 it will be seen that as this piston 4 rises, a partial vacuum will be produced beneath it and an explosive mixture will be drawn in from the chamber 12, past valve 13 to the cylinder 3 below the piston 4. When this piston begins to descend the explosive mixture is forced out through the 90 valve 16 into the interior of the case 1. Consequently the interior of case 1 is always 95 filled with explosive mixture.

Now the casing 1 is apertured intermediate the cylinders 3 and I provide tubes 105 such as 17 connecting with said apertures which lead radially outwardly from the casing 1 intermediate the explosion cylinders 3. At their outer ends the tubes 17 connect with pipes 18 which connect in turn 110 with the interior of valve casing 19. Before describing the function of the appara-

tus within the valve casing 19 I wish to call attention to the arrangement shown in Fig. 6 from which it will be seen that the sliding pieces 15 have a circular section in the plane 5 perpendicular to the pivot 8 and are held in close fitting engagement with the flanges 6 by means of cross pieces 14. It will be further seen from Fig. 6 that I provide a gland 7' on each of the sliding members 15 which may be packed so as to prevent leakage from the interior of the casing 1 to the interior of explosion cylinders 3. At the pitmans 7 assume different positions during the revolution of the engine, the members 15 slide or run side by side to accommodate themselves to the movement of the pitmans, but are of sufficient length so that they always cover the inner end of the cylinders 3. Being of the length just mentioned they 10 must necessarily project through the cylinder casing 1 and I have utilized the tubes 17 to afford room or space into which they may project.

Referring again to the valve casing 19, as best shown in Fig. 9, these cylinders contain valves such as 20 which comprise rods 21 upon which are mounted three pistons 20'. Now the pipes 18 connect with the valve casing 19 about the center thereof, and somewhat removed toward the outer end of the casing 19 the connection is taken off to a hollow annulus 7' which surrounds the outer ends of the explosive cylinder 3 somewhat to one side of the center thereof. Now the inner ends of the rods 21 extend through the cylindrical casing 1, as clearly shown in Fig. 7, and at their inner ends they are pivotally connected to a ring 22' which is adapted to revolve around the outer surface 30 of a fixed eccentric 22 which is rigid with the fixed shaft 23. When the valves 20 are placed in the proper position the carbureted mixture can pass from the casing 1 into the annulus 7'. Within the annulus 7' is a 35 sleeve valve 24 which comprises a ring member 26 which fits against the inner surface of the annulus 7' and which carries at proper intervals pistons 25, said pistons dividing the space within the annulus into 40 suitable chambers as clearly shown in Fig. 5. Now each cylinder 3 connects with the annulus 7' by means of a short passage 8' which serves both for inlet and exhaust, and when both the sleeve valve and the valves 20 45 are in proper position explosive mixture passes through casing 19, annulus 7', and passage 8' into the cylinder 3. The sleeve valve 24 is rotated within the annulus 7' in the direction opposite to the rotation of the engine as a whole, it being understood that the cylinders revolve in the direction shown by the arrow in Fig. 5. The movement of the sleeve valves relative to the annulus 7' is caused by a sprocket wheel 27. The annulus is cut away at one point to permit the

teeth of the sprocket to project within it. The ring member 26 is provided with notches such as 26' for the reception of the teeth on the sprocket wheel 27. Now the sprocket 27 is carried on a shaft 28 which, as best shown in Fig. 4, is supported by a bracket extending from the casing 1. At the outer end of the shaft 28 is a second sprocket wheel 27' which is driven by a sprocket chain 33, which passes around the fixed wheel 34 previously mentioned. After the charge in a given cylinder has been exploded, the sleeve valve 24 assumes a position in which the passage 8' is connected with the appropriate outlet 9, there being one of the outlets 9 in the outer face of the annulus 7' for each of the explosion cylinders 3.

Now as is best shown in Fig. 4, the inlet valve casings 19 are situated at one side of the cylinders 3 and on the opposite sides thereof are similar valve casings 32. As shown in Fig. 2, within the casings 32 are valves of a construction similar to the previously described valves 20. Valve casings 32 are connected by pipes such as 31 and it will be seen that each pipe 31 is farther from the center of the casing 1 at one end than it is at the other. It will also be seen that each pipe 31 is provided with a connection 50 which leads to the interior of one of cylinders 3. The valves 32' are provided with rods 51 which are operated from an eccentric 42 on the shaft 30 in a manner similar to the previously described operation of the rods 21. When valves 32' are in proper position a passage way is open from one of the cylinders to the one adjacent to it but in the rear thereof with reference to the direction of rotation. By this connection a hot blast is admitted from one cylinder to the next for the purpose of affecting explosion.

Fig. 5 shows the motor in the position ready to start. Sleeve valve 24 being divided as shown into seven sets of chambers by the pistons 25 one set for each explosion cylinder and each set of chambers contains three chambers formed by similar intermediate pistons. Two of the last mentioned 115 chambers are of equal size and are just long enough so that they will not reach from the top port or passage 8' leading into the cylinder to the outlet or exhaust port 9 while the third chamber of each set is 120 of greater length for a purpose which will presently appear. The first of the two small chambers in each set serves to lead the explosive mixture from the valve casing 19 into the explosion cylinders through the ports 8'. The second of the two small chambers in each set is in communication with the port 8' during the explosion and expansion in the cylinders 3, while the larger chamber 35 of each set 130

serves to lead the exhaust gases from the port 8' to the port 9. As shown the valves are so timed that they will be admitting new gas into the cylinders and exploding during a half-revolution of the complete structure, and exhausting during the other half, although I do not wish to be limited to such specific timing. Now the engine being in the position shown in Fig. 5, an initial explosion is caused by means of a spark plug 29 shown in Fig. 7, said spark plug being connected with a conductor 29' which is connected in turn to an insulated ring 30 which is charged from some suitable exterior source of electricity. An explosion having been produced in the lower cylinder by means of the spark plug 29, the valves 32 serve to admit a hot blast from one cylinder to the next at the proper time in order to explode the latter. In this way the engine is made entirely self igniting and the troubles due to the usual ignition apparatus are avoided.

It will be apparent that the valves 20 and 32 being of the balance type will be able to withstand the pressure caused by the explosion and yet may be moved by a small impulse. It will be understood, however, that I do not mean to limit myself to any particular form of valve for controlling the inlet of the explosive mixture or the passage of the hot blast from one cylinder to the next.

Power is taken from the engine by means of the sprocket 40 which is rigid with the side of the cylindrical casing 1, but it will be evident that if desired, power may be taken from the engine by revolving the shaft instead of the cylinders, it being intended, however, in the present case to revolve the cylinders.

It will be observed that as shown in Fig. 5, the pitmans 7 connect the two yokes such as 41 which are bolted together surrounding the fixed crank pin 23' which is rigid with, but radially displaced from the shaft 23. The pitmans 7 being pivoted to the pistons as previously mentioned are also pivoted to the yokes 21 in order to permit proper swinging motion of the pitmans, except in the case of one out of each of the three pitmans connected to each yoke, one of the three being rigidly attached to the yoke so that the latter may be revolved.

It will be understood by those skilled in the art that while I have shown and described herein the preferred form of my invention, various modifications and rearrangements thereof may be made without departing from the spirit of my invention, and that parts of my invention may be used without utilizing the whole.

Having thus described my invention, what I claim is:—

65 1. A gas engine comprising in combina-

tion, a plurality of explosive cylinders mounted with their axes in a given plane, a tube having communication with all of said cylinders, valve means mounted within said tube adapted to control the inlet and exhaust of said cylinders, and means for moving said valve means longitudinally of said tube.

2. A gas engine comprising in combination, a plurality of explosive cylinders, said cylinders being mounted in a given plane at right angles to the axis of rotation, a tube surrounding the outer end of said cylinders and having communication with each of them, said tube also being provided with apertures serving as exhaust ports, means for introducing explosive mixture into said tube, and a valve structure mounted in said tube adapted to control the admission of explosive mixture into said cylinders and the exhaust of gases therefrom, said valve structure comprising piston members dividing the space within said tube into inlet, explosion and exhaust chambers, the total number of said chambers being equal to three times the number of cylinders plus three.

3. A gas engine comprising in combination, a plurality of explosive cylinders mounted in a given plane at right angles to the axis of rotation, a tube surrounding the outer end of said cylinders and communicating with each of them, said tube being provided with ports for communicating with said cylinders and also with ports for exhaust purposes, a valve structure mounted within said tube comprising ring sections 26 contacting with the inner face of said tube and pistons 25 dividing the space within said tube into inlet, explosion and exhaust chambers, said chambers being arranged in sets of three and there being one more set than there are explosion cylinders, and means for moving said valve structure relatively to said tube in a direction opposite to the direction of rotation of the engine.

4. An explosion engine comprising in combination, a plurality of explosive cylinders arranged radially about the axis of rotation, a tube surrounding the outer ends of said cylinders and having communication therewith, a valve structure mounted within said tube for governing the inlet and exhaust of said cylinders, said valve structure comprising ring sections bearing against the face of said tube and having recesses therein, pistons separating the space within said tube into chambers and having operative connection with said ring sections, and a sprocket wheel extending through an aperture in said tube and having operative engagement with the recess of said ring sections whereby said valve structure is operated.

5. An explosion engine comprising in combination, a central cylindrical casing, a

2. plurality of explosion cylinders mounted radially around said casing, a hollow ring surrounding the outer ends of said cylinders and having ports communicating therewith and having other ports serving as exhaust ports therefor, a sleeve valve mounted within said ring for controlling the admission of explosive mixture and exhaust of gases from said cylinders, means for operating said sleeve valve, means for forcing explosive mixture into the interior of said casing, and valve means for controlling the admission of explosive mixture from said casing into said ring.
3. 6. A gas engine comprising in combination, a central cylindrical casing, a plurality of engine cylinders mounted radially around said casing, pistons within said cylinders, a crank within said casing, pitman rods connecting said pistons with said crank, heads separating said cylinders from the interior of said casing, sliding plates mounted in said heads, through which said pitman rods pass, valve means for leading explosive mixture into said cylinders between said heads and said pistons, valve means whereby said explosive mixture may be forced from said cylinders into the interior of the casing, valve means for admitting explosive mixture from said casing into the outer ends of said engine cylinders, and means for producing explosions in said cylinders.
4. 7. A gas engine comprising in combination, a plurality of explosion cylinders mounted with their axes in a given plane and radiating from a given point, a tube having communication with all of said cylinders, valve means mounted within said tube adapted to control the inlet and exhaust of said cylinders, and means for moving said valve means longitudinally of said tube.
5. In testimony whereof I affix my signature in the presence of two witnesses.

GUSTAVE ADOLPH WENDT.
